PENDANT CLUSTER LOUD-SPEAKER OR
SIMILAR ARTICLE

Walter Tony Charlton, Winnipeg, Manitoba, Canada,
assignor to The Seeburg Corporation, Chicago, Ill.

Filed Mar. 23, 1964, Ser. No. 79,132

Term of patent 14 years

(Cl. D26—14)

FIGURE 1 is a perspective view of a pendant cluster loud-speaker or similar article showing my new design;

FIGURE 2 is a side elevational view of one of the four sides thereof, to a reduced scale, the remaining three sides being identical thereto;

FIGURE 3 is a top plan view to a reduced scale; and
FIGURE 4 is a bottom plan view thereof.

I claim:

The ornamental design for a pendant cluster loud-speaker or similar article, substantially as shown and described.
